[57] CLAIM

The ornamental design for a childrens football helmet bed, as shown and described.

DESCRIPTION

FIG. 1 is a front elevational view of the childrens football helmet bed showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a left side elevational view, showing the face guard in elevated position; the broken lines are for environmental purposes only and form no part of the claimed design.

*FIG. 1**FIG. 2**FIG. 3*

FIG. 4

*FIG. 5**FIG. 6**FIG. 7*
